UNITED STATES PATENT OFFICE.

LOUIS O. ANDERSON, OF BRUNSWICK, MINNESOTA.

STORM-COVER.

1,284,968.

Specification of Letters Patent. Patented Nov. 19, 1918.

Application filed May 16, 1918. Serial No. 234,993.

To all whom it may concern:

Be it known that I, LOUIS O. ANDERSON, a citizen of the United States, residing at Brunswick, in the county of Kanabec and 5 State of Minnesota, have invented certain new and useful Improvements in Storm-Covers, of which the following is a specification.

My invention relates to a storm cover for 10 either permanent or emergency attachment to a boat in order to exclude water and protect the occupant.

The many objects and advantages will be 15 pointed out in relation to accompanying drawings of one preferred embodiment as described hereinafter.

However, attention should be called to the desiderata to provide a storm cover having a suitable body cover or suit for the occupant forming part thereof; one with suitable clamping means to join the cover to the boat; one having strap or other means to fasten the cover in position preparatory to clamping; means to permit access to the exterior of the boat; and a means utilizing one or more of the propelling oars of the boat to ridge or raise the cover at the center so that water will immediately drain or run off of the cover.

30 In the said drawings:—

Figure 1 is a perspective view illustrating my improvement associated with a boat and its occupant;

Fig. 2 is a view of the boat and its improvements, mostly in longitudinal section;

Fig. 3 is a view looking toward the bow but with the upper portion in transverse section along the line 3—3 of Fig. 2;

Fig. 4 is a detailed perspective view of 40 one of the supporting ridges for the cover;

Fig. 5 is a detailed cross sectional view on the line 5—5 of Fig. 2;

Fig. 6 is a fragmentary perspective view illustrating one of the straps of the cover 45 and its connection to the cover, and

Fig. 7 is a disassembled fragmentary perspective view of a longitudinal and transverse clamping bar for the cover, at the joint.

50 The invention may be practised in con-

nection with any suitable type of boat, particularly those propelled manually, and for instance the row-boat conventionally shown at 8. This boat has gunwales at 9 and a deck in fore and aft sections respectively at 10 and 11. An oar lock 12 is disposed centrally at the stern for reception of an oar like 13 in Fig. 1 to be operated in the manner suggested in that figure. Below the gunwales, a suitable number of ports 14 are 60 provided in the sides of the boat, in order that water may be removed from the boat.

A cover or canopy 15 is provided to cover the exposed top portion of the boat, and be 65 removably or permanently secured to the boat. This cover or canopy may be made of any suitable material which is waterproof, for instance a rubberized fabric. At opposite ends, straps 16, of leather or other suitable material are stitched at 17 or otherwise fastened to the cover. These straps pass through staples or anchors 18 rising from the deck sections 10 and 11 and are fastened together by a suitable separable fastening at A which for example may essentially comprise an eyelet 19 which is engaged by a hook 20 which may have a flexible locking lug adapted to yield when the hook engages the eyelet and which then springs outwardly to lock the eyelet against 75 accidental detachment.

A suitable means is provided to secure the cover or canopy at its lower edge to the boat so that water cannot enter at the joints. To this end, clamping bars 22 are disposed longitudinally of the boat and rest on the edge portion of the cover disposed between the clamping bars and the gunwales 9, as well shown in Fig. 3. Any suitable means may be used to clamp the bars in place, for instance bolts 23 which receive clamping winged nuts 24. Transverse clamping bars 25 are also employed to rest on a portion of the cover between the same and the deck sections. These clamping bars 25 may have 95 projections 26 overlapping bars 24 and said projections provided with apertures to register with the apertures of bars 22 through which the bolts 23 pass, so that the bolts may pass through both bars 22 and 24. The 100

degree of clamping of the bars against the cover is regulated by tightening of the nuts 24.

Built into the structure of the cover 15, 5 is a suit of the same material as the cover designated 27. The occupant may enter this suit to propel the vessel in the manner shown in Fig. 1, preferably standing. In 10 propelling the vessel, the operator must turn, and therefore the suit is made full at its junction with the cover as at 28. This suit may comprise arms 29, a head 30, a window 31, an airtube 32, a life preserver 33, and a belt 34. Life preserver 33 is preferably 15 a U-shaped ring of the same material as the suit and fastened thereto and filled with cork or other buoyant material 35. Belt 34 is fastened to the interior of the suit and the occupant may fasten it around his 20 body. I also provide a suitable waterproof entrance at 36, so that the occupant may enter the boat therethrough, but the construction of which is unnecessary to specifically describe. The occupant may receive 25 the necessary air through the tube 32 and through an opening 37 in the deck section 10, normally covered by a sliding water tight door 38 mounted in guides 39, and being operable by a handle 40.

30 When the cover is in use, it is desired for it to be higher at the center as can be best seen from Fig. 3. To this end, I employ preferably a plurality of bridge plates 41 having notches 42 to receive the gunwales, 35 clamping bars 22, and the adjacent portion of the cover and having a notch at 43, centrally in its upper edge. In attaching these plates, it will be understood that they are first disposed at an angle, and then moved 40 transversely of the boat in order to receive and frictionally engage the parts mentioned in the notches 42 to thus maintain the bridges in place. By reason of the shape of the upper portion of the bridges, the 45 cover is raised and water will effectively drain therefrom. The notches 43 may receive therein, one of the oars 13 as shown in Figs. 2 and 3, thus the ridging is effectively provided from the bows to the suit 27.

50 It will be understood, that one oar in cases of emergency during a storm, may be used to propel the boat while the other is used to ridge the cover 15.

As previously explained, the improvements 55 may be permanently attached to a vessel or may be used as an emergency covering. If used as an emergency covering, cover 15 with the suit may be compactly folded and carried on the boat, with the 60 bars 22 and 25 removed or joined in place as desired. In attaching the cover, one of the straps 16 is first connected to the anchor 18, and then by the aid of draw strings or the like 44, preferably provided both

interiorly and exteriorly of the cover, is unfolded and positioned so that the other strap 16 may be secured in place. After thus positioning the cover, the clamping bars 22 and 25 may be applied, and finally the bridges and selected oar 13 may be positioned as shown in Fig. 2.

If for any reason, the protected vessel should attempt to sink, the life preserver 33 will save the occupant. It will be understood of course that the cover may be 75 detached from the boat, if desired, for salvage if the occupant must depend upon the life preserver.

Since merely one preferred embodiment has been illustrated and described, let it 80 be understood that changes in the details in construction may be resorted to without departing from the spirit and scope.

I claim:

1. In a boat, an emergency storm cover, 85 clamping bars separate from the cover and the boat to secure the cover intermediate the bars and the boat, fastening means passing through the clamping bars beyond the edges of the cover to avoid piercing thereof, 90 and said fastening means being removable for the purpose specified.

2. In a boat, an emergency storm cover, substantially longitudinally disposed and substantially horizontally disposed clamping 95 bars, said clamping bars overlapping, and removable fastening means passing through the bars at the overlapping portions and through the upper portion of the boat beyond the edges of the cover.

3. A boat having a removable and collapsible storm cover, straps associated with the cover and collapsible therewith after removal, anchors on the boat to detachably receive the straps to fasten the cover in position, and removable bars resting on the cover to clamp the cover between the bars and the boat after positioning thereof.

4. A boat having a removable and collapsible storm cover, straps associated with the 110 cover and collapsible therewith after removal, separable fastenings for the straps, anchors on the boat to detachably receive the straps to fasten the cover in position, and removable bars resting on the cover adjacent its marginal edge to clamp the cover between the bars and the boat after positioning thereof.

5. A boat having a storm cover, and removable means engageable with the cover 120 supported from the boat by frictional engagement therewith to raise the cover to shed water.

6. A boat having a storm cover, a riser 125 removably supported from the boat, and means separate from the cover removably supported by the riser to raise the cover to shed water, and said means being insert-

ible from within the boat below the cover by movement substantially longitudinally of the cover.

7. A boat having a storm cover, a removable bridge to raise the cover to shed water, and said bridge being notched to receive a part of the boat for support.

8. A boat having a storm cover, clamping bars securing the cover against the gunwales, a removable bridge to support the

cover in raised position to shed water, and said bridge being notched to receive the gunwales, clamping bars and adjacent portion of the cover for support.

In testimony whereof, I have affixed my 15
signature in the presence of two witnesses.

LOUIS O. ANDERSON.
